UNITED STATES PATENT OFFICE.

JOSEPH GOTTSCHALK, OF BALTIMORE, MARYLAND.

BILL-FILE.

SPECIFICATION forming part of Letters Patent No. 349,792, dated September 28, 1886.

Application filed March 2, 1886. Serial No. 193,801. (No model.)

To all whom it may concern:

Be it known that I, JOSEPH GOTTSCHALK, of Baltimore city, State of Maryland, have invented a new and useful Improvement in Bill- 5 Files, of which the following is a specification.

My invention relates, generally, to that class of paper-files in which are employed puncturing and transfer wires movable apart; and it consists in the novel devices by which the 10 wires may be held apart when so adjusted, and in certain other features of construction and combinations of parts, as will be described.

In the drawings, Figure 1 is a perspective view of my improvement. Fig. 2 is a detail 15 view of the hinged plate. Fig. 3 is a sectional view of the base and hinged plates A D.

In use a plate, A, is secured on a suitable board or base, B. On this plate are mounted the puncturing-wires C C, which are preferably hollow, forming tubes. 20

To the plate A is hinged the plate D, which is provided with the transfer wires or hooks E, the points of which are movable into and out of contact with the points of the puncturing-wires. A spring, F, is arranged to bear 25 under the plate D, and serves to keep the wires C and E normally in contact, as shown. An arm, G, is connected with the plate D at or near its movable edge, and extends laterally 30 from such plate to a point about in line with the side of the board B. It is preferred to form this arm integrally with the plate D, and also to depress slightly its outer portion, g, so the same may move into a groove or slot, b, in 35 the base-board when moved to adjust the wires C E apart. A latch, H, is preferably used to secure the arm G when depressed. To this end it is also preferred to form the base with a groove, b, to receive the dropped portion g 40 of the arm. This latch H, in the construction shown, is formed of a bar, h, having its point 1 movable over the path of the arm G, and projected, when at rest, over the groove b, when such groove is employed. This bar is 45 usually sunk below the face of the board B, and is covered by a plate, I, as shown. To render this latch automatic in engaging the arm G, I provide a spring, 2, which engages

it and gives it a constant forward tension. A bar, J, is connected with and extended laterally outward from the latch-bar h, and to obviate any projection beyond the side of base-board B it is usual to form a mortise, 3, in the side of the board and arrange the handle of the latch therein. It will be noticed that arm 55 G furnishes a simple handle by which the plate D may be adjusted as desired from the side of the board B and out of the way of the papers held on the wires. By the arrangement of the latch devices the plate D, when held down to 60 adjust the wires apart, may be released from the side of the board, as will be seen.

While it is preferred to provide the plate A with a section of the hinge and to pivot the plate D thereto, it will be understood that the 65 plate D might be hinged directly to the board. The construction as shown, however, is simple, and enables the proper connection of the improvement with a base or board to be easily effected. 70

Having thus described my invention, what I claim as new is—

1. In a bill-file, a plate or carrier having transfer-wires and provided with a lateral handle-arm, substantially as set forth. 75
2. A bill-file comprising the plate having the transfer-wires and hinged at one edge, an arm extended laterally from the movable edge of such plate, and a latch arranged to engage such arm, substantially as set forth. 80
3. In a bill-file, the combination, with the base having a groove, b, and the hinged plate having the transfer-wires, of the arm extended from said plate and having its outer end movable into and out of groove b, and a latch movable over groove b, substantially as set forth. 85
4. In a bill-file, the combination of the support or base having a side mortise, 3, the plate having a lateral arm, and a latch arranged to engage said arm, and having a lateral handle 90 projected into and movable within the mortise 3, substantially as set forth.

JOSEPH GOTTSCHALK.
